UNITED STATES PATENT OFFICE.

J. J. DUTCHER, OF NEW HAVEN, CONNECTICUT.

IMPROVEMENT IN STEAM-BOILERS.

Specification forming part of Letters Patent No. 13,425, dated August 14, 1855.

To all whom it may concern:

Be it known that I, J. J. DUTCHER, of the city and county of New Haven, and State of Connecticut, have invented certain new and useful Improvements in Boilers for Locomotives and other Steam-Engines and for other Purposes; and I do hereby declare that the following is a full, clear, and exact description of the same, reference being had to the accompanying drawings, forming part of this specification, in which—

Figure 1 is a central longitudinal vertical section of the body and smoke-box of a locomotive-boiler constructed according to my invention. Fig. 2 is a transverse section of the same in the line $x x$ of Fig. 1. Fig. 3 is a transverse section of the same in the line $y y$ of Fig. 1.

Similar letters of reference indicate corresponding parts in the several figures.

A is a horizontal cylinder, forming the exterior of the body of the boiler extending from the fire-box to the smoke-box B in the same manner as the external cylinder of the common locomotive-boiler.

C D are two horizontal cylinders of similar diameter, smaller than A, and arranged end to end within it. The cylinder C is united with the fire-box of the boiler by the hollow frustum of a cone a , of which the base connects with the cylinder C, and the truncated end opens into the fire-box. At the opposite end this cylinder D contains the hollow frustum of a cone b , the base of which unites with the end of the cylinder and the truncated end with an inclined descending pipe c , which passes through the upper side of the cone a . The end of the cylinder D nearest to C is connected to the base of a hollow frustum of a cone d , which enters into the cone b in such manner that a space e is left between the two cones. The other end of the cylinder D contains the hollow frustum of a cone f , the base of the said cone uniting with the cylinder and the truncated end uniting by a pipe g with the truncated end of the cone d .

There is a communication between the cylinders C and D through a pipe or passage h , which connects the lower sides of the cones $b d$; and from the cylinder C there is a passage l through the cone f and the head i to the smoke-box B. The smoke or inflammable gases and heated products of combustion pass from the fire-box through the cone a , cylinder C, passage h , cone d , cylinder D, and

passage l to the smoke-box. The water circulates around the cone a and cylinder C, through the pipe c , between the cones e and d , through the pipe g , and passage l , and around the cylinder D, having a complete circulation both through and around the flues.

In order to form cavities in which the inflammable gases may be arrested and burned, I cut holes or leave in the sides of the cylinders C and D, and cover the said holes with long cups $j j$, the insides of the cups being toward the interior of the cylinders, and in order further to increase the heating-surface I make other openings which I cover with other cups $k k$, the inside or cavity of which is next the water-space, and the exterior enters the interior of the cylinders. From the sides of the cone a small conical chambers $m m$ enter the water-space, and similar cones $n n$ enter the water-space from the head i of the boiler, and from the sides of the cone f cones $m' m'$, of an opposite character to m and n to contain water, enter the flue. The cones m and n serve the same purposes as the cups $j j$, and the cones $m' m'$ serve the same purpose as the cups $k k$. At the bottom of the cylinder D there is a segment-shaped water-chamber o (see Figs. 1 and 3) entering the said cylinder. This serves to check the draft at the bottom and throw it around the upper part of the cylinder D and cone f before it can escape at the passage l to the chimney.

By experiments with a boiler of this kind and a tubular boiler of the kind ordinarily used for locomotives I find that steam is raised in this boiler in a much shorter time and with a much less quantity of fuel.

What I claim as my invention, and desire to secure by Letters Patent, is—

1. Placing within the cylindrical water-body B of a boiler one or more cylindrical flues C or D, terminating at their ends in frustums of cones, which frustums all have the truncated ends toward the fire-box and the bases toward the chimney and serve to form communication through the cylinders from the fire-box and toward the chimney, substantially as herein set forth.

2. The arrangement of the two cylinders C D, cones $a b d f$, pipes $c g$, passages h and l , as herein fully described.

J. J. DUTCHER.
